UNITED STATES PATENT OFFICE.

FRANK W. MERRICK, OF BOSTON, MASSACHUSETTS.

GROOVE-CUTTING ATTACHMENT FOR SEWING-MACHINES.

SPECIFICATION forming part of Letters Patent No. 547,961, dated October 15, 1895.

Application filed January 14, 1895. Serial No. 534,774. (No model.)

To all whom it may concern:

Be it known that I, FRANK W. MERRICK, a citizen of the United States, residing at Boston, in the county of Suffolk and State of Massachusetts, have invented certain new and useful Improvements in Groove-Cutting Attachments for Sewing-Machines, of which the following is a specification, reference being had therein to the accompanying drawings.

10 My prior patent, granted January 31, 1893, No. 490,855, presents a sewing-machine having a work-supporting post that is pivoted at the lower end thereof to the frame of the machine, so as to enable it to be swung down 15 and to one side out of the way when desired.

My present invention has for its main object to provide a groove-cutting attachment that is especially adapted for application to a work-supporting post, which is pivoted as in 20 the said patent, although it is to be understood that I do not limit my invention to use in such connection.

The invention consists in certain novel and improved features of construction and combination, all as hereinafter will be made clearly to appear, and first will be described fully with reference to the accompanying drawings, after which the distinguishing and characteristic features thereof will be more 30 particularly pointed out and distinctly defined in the claims at the close of this specification.

The invention is simple and will be understood readily from the following description 35 and accompanying drawings.

Figure 1 of the drawings is a view in side elevation, partly sectional, of part of a sewing-machine having my invention applied thereto. Fig. 2 is a view in elevation, partly 40 sectional, from the left-hand side in Fig. 1. Fig. 3 shows the groove-cutter detached.

In the drawings is part of the fixed bed or frame of a sewing-machine; 2 is the rocker-shaft for actuating the cast-off; 21 is the cast-off operated from said shaft in the usual manner; 22 is the needle-bar; 23 is the needle, and 45 3 is the work-supporting post, the said post being pivoted at its lower end to the said fixed bed or frame on centers at 4, and being provided with suitable locking devices 5, whereby 50 to hold it in normal working position. All the foregoing parts and features are or may be as

heretofore, and are well-known in practice, and may be connected and arranged in any approved manner. At 6 is the throat-plate, 55 mounted on the upper end of the work-supporting post, it having on its upper face, at the sides of the slot 7, in which plays the groove-cutter about to be described, the serrations 8, which prevent the leather from moving under the action of the cutter as the latter makes its stroke in cutting.

9 is the groove-cutter, it being carried by the upper end of an upwardly-extending arm 10, fixed upon one end of a rock-shaft 11. 65 The said rock-shaft has a bearing or bearings at 12 in the portion 13, cast with the work-supporting post 3, and at its other end it has fixed thereon the depending arm 14. The said rock-shaft and its arms I term for convenience a "rocker." A spring 15 has a number of coils which surround the outer end of the bearing portion 13, one end of the said spring being in engagement with a pin 16, projecting from the said portion 13, and the other end 70 being in engagement with a lug 17, projecting from arm 14. The lower end of arm 14 extends approximately down to a point in line with the center on which the work-supporting post turns, and is formed with a cam-surface 75 18, that is acted against by a tappet constituted by a pin or roller 19, carried by the free end of an arm 20 on the cast-off rocker-shaft 2. The portion 181 of the said cam-surface 18 is shaped, as shown, to be concentric with 80 the cast-off rocker-shaft, while the pin or roller 19 is resting against the same, so that while the said pin or roller is passing either up or down along such portion no movement is communicated to the cutter. The lower portion 182 of the said cam-surface is shaped so that when the pin or roller touches the same in its descent it will press the arm 14 in a direction to move the cutter to form a groove in the leather resting upon the throat-plate. As 85 the pin or roller rises the spring 15 moves the parts reversely until the pin or roller reaches the portion 181 of the cam-surface.

The lower end of the arm 10 is formed with an eye or socket 211 to fit upon the rock-shaft 105 11, the said eye or socket being threaded for the reception of the two set-screws 215 215. The end of the rock-shaft 11 is slabbed off at 216 216 to form oppositely-located shoulders

217 217. The inner ends of the set-screws 215 take bearing against the said shoulders, and thereby serve to secure the arm 10 in the desired position of adjustment circumferentially of the rock-shaft. Thereby the normal position of the groove-cutter may be regulated, as desired. The upper end of the said arm is formed with a split socket 231 to receive the shank or stem of the groove-cutter 9, the said 5 socket being tightened upon the groove-cutter by means of a screw 24, working in ears at the free ends of the opposite arms of the socket 231. The groove-cutter may be adjusted readily in the direction of its length in the said socket.

15 The groove-cutter 9 consists of a simple rod, preferably having its upper end tapered off somewhat, as shown, the said rod being grooved, as at 26, on one side by the use of a 20 suitable milling - cutter, the groove being shaped as shown to leave an overhanging edge 27 at its upper end, which is ground off on its top so as to sharpen and fit it for cutting purposes.

25 I claim as my invention—

1. The combination of a groove-cutter, and a rocker carrying the same, with the fixed bed or frame of the machine, a work-supporting post pivotally connected with said bed or 30 frame and capable of being swung down out of the way, said post having said rocker mounted thereon and moving therewith, and a shaft mounted in the fixed bed or frame and carrying a tappet which engages with the 35 rocker to actuate the same and the groove-cutter, substantially as described.

2. The combination with the work-supporting post, and a throat-plate carried thereby, of a groove - cutter, an arm by which the 40 groove-cutter is held, a rock-shaft journaled in said post and on which said arm is fixed, a

second arm fixed on said rock-shaft, a second rock-shaft, an arm on said second rock-shaft having a tappet which acts on the second arm to move the same in one direction, and a 45 spring acting oppositely to the said tappet, substantially as described.

3. The combination with a groove-cutter, an arm by which the groove-cutter is held, a rock-shaft on which said arm is fixed, and a 50 second arm fixed on said rock-shaft, of a shaft having a tappet which acts on the said second arm to move the same in one direction, a spring acting oppositely to the said tappet, a fixed bed or frame on which the tappet-shaft 55 has bearing, and a work-supporting post on which said rock-shaft has bearing, said post being pivoted to the fixed bed or frame and the tappet being arranged to engage with the second arm aforesaid approximately in line 60 with the pivots of the post, substantially as described.

4. The combination with the groove-cutter, of an arm carrying the groove-cutter and provided with an eye or socket, a rock-shaft on one 65 end of which said eye or socket is fitted and having oppositely located shoulders at such end, set screws passing through the eye or socket and taking bearing against such shoulder, whereby to secure the arm in the desired 70 position of adjustment circumferentially of the rock-shaft, a second arm on said shaft, and means acting upon said second arm to vibrate the rock-shaft and groove-cutter, substantially as described.

75 In testimony whereof I affix my signature in presence of two witnesses.

FRANK W. MERRICK.
